FIG. 3.

FIG. 4.

J. P. Niper
Inventor

By *Geo. P. Kimmel.*

Attorney.

UNITED STATES PATENT OFFICE.

JESSE P. NIPER, OF ALLAMUCHY, NEW JERSEY.

DIRECTION-INDICATOR.

1,311,289.

Specification of Letters Patent. Patented July 29, 1919.

Application filed April 12, 1917. Serial No. 161,451.

To all whom it may concern:

Be it known that I, JESSE P. NIPER, a citizen of the United States, and resident of Allamuchy, in the county of Warren and State of New Jersey, have invented certain new and useful Improvements in Direction-Indicators, of which the following is a specification.

This invention relates to signals and has 10 more especial reference to an improved direction indicating signal for motor vehicles.

The invention has for its dominant object to provide a signal operable from the driver's seat of a motor driven vehicle, whereby the 15 course to be taken by the vehicle can be previously signaled to drivers of vehicles in the rear and pedestrians.

It is another and equally important object of the invention to provide a novel support 20 for the signal means proper, the said means serving to efficiently support the signal means, to prevent the splashing of mud and the like thereon, and also as light ray reflecting means for projecting the light directly 25 onto the signal means.

A further object of the invention is to provide an improved form of signal having a plurality of directions and symbols thereon and being rotatably mounted to permit 30 the independent displaying of such directions and symbols.

The improvements in the details and arrangement of parts will be apparent from an inspection of the accompanying drawings, 35 in connection with the specific description hereinafter contained, and wherein the preferred embodiment of the invention is disclosed for the purpose of imparting a full understanding of the same.

40 In the drawings:

Figure 1 is a side elevation of the improved direction indicator as applied to a motor driven vehicle;

Fig. 2 is a front elevation of the signal;

Fig. 3 is a side elevation thereof; and

Fig. 4 is a fragmentary side elevational view with parts thereof broken away and shown in section.

Referring now more particularly to the 50 drawings and in connection with which like reference characters will designate corresponding parts throughout the several views, there is provided a curved hood member 1 having apertured arms 2 secured to the rear

sides thereof whereby the same may be 55 mounted upon the rear of the motor vehicle M, preferably on one of the elliptical springs thereof through the medium of bolts or similar fastening devices which are passed through certain of the apertures formed 60 therein. It is to be noted, that the inner surface of the hood 1 is highly polished and, obviously, serves as a light ray reflecting means, the purpose of which will be subsequently apparent. Apertured lugs 3 are 65 formed upon the hood 1 and are bent at substantially right angles thereto, whereby the signaling means proper, which will be hereinafter more fully described, may be rotatably supported therebetween.

A box 4 having alined openings formed in the end portions thereof is rotatably mounted between the lugs 3 by means of a pivot bolt 5 which is passed therethrough and has its opposite ends so connected as to prevent 70 lateral displacement thereof. Directions and symbols indicating the various courses and movements of the vehicle are cut into the side walls of the box 4 while to one side thereof circular openings are formed. Over 75 the direction indicating matter, transparent panes are arranged while over the circular openings formed to one side thereof, colored glass inserts are positioned and serve as the usual danger signaling means commonly employed upon the end lights of various types 80 of vehicles. A pinion 6 is secured to one end wall of the box 4 and is engaged by a rack 7 formed upon an operating bar 8 extending longitudinally of the vehicle body to a position 85 adjacent the driver's seat, whereat, the same is pivotally engaged by a lever 9. A rack 10 is provided for the lever 9 and serves as means for maintaining the same in an adjusted position. The connecting bar 8 is 90 formed of a plurality of sections, which sections are united by a suitable clamp 11 arranged over the adjacent extremity. By loosening the clamp 11, relative adjustment 95 of the several sections of the connecting bar 100 may be made to accord with the length of the vehicle upon which the signaling device is to be arranged.

Referring to the apertured arms 2 as secured to the rear side of the hood 1, it is to 105 be noted that the lowermost openings formed therein serve as means for allowing the attaching of the usual motor vehicle license

tag thereto, the said tag being illuminated due to the projecting of the light rays from a light source arranged within the rotatable box 4 thereonto.

5 To operate my improved signaling device, the lever 9 is rocked to the desired extent, whereupon certain of the direction indicating matter as formed in the various side walls of the box 4 will be brought into 10 playing position. By this means, drivers of following vehicles as well as pedestrians will be fully informed of the movement to be made by the vehicle.

If desired, suitable matter may be arranged upon the rack 10 to indicate and facilitate the selection of the proper indicating matter.

Manifestly, the construction shown is capable of considerable modification and such modification as is within the scope of my

claim, I consider within the spirit of my invention.

I claim:

A direction indicator, comprising a hood having end walls formed with bearings and its inner surface polished to provide a reflector, a lamp box mounted in said bearings in the hood for rotation on a horizontal axis, said lamp box having one wall open, a translucent sign arranged adjacent the open wall, 30 a rack gear on one end of said lamp box, a horizontal rack bar mounted for sliding movement and meshing with said gear; and held in meshing engagement by the hood, and a lever connected to said rack bar for 35 imparting reciprocatory movement thereto.

In testimony whereof, I affix my signature hereto.

JESSE P. NIPER.
